UNITED STATES PATENT OFFICE.

HJALMAR LÖFQUIST, OF STOCKHOLM, SWEDEN.

ELECTRIC HEATING DEVICE FOR RUNNING WATER.

1,030,901.

Specification of Letters Patent.

Patented July 2, 1912.

Application filed October 6, 1911. Serial No. 553,186.

To all whom it may concern:

Be it known that I, HJALMAR LÖFQUIST, a subject of the King of Sweden, residing at 21 Birger-Jarlsgatan, Stockholm, Sweden, 5 have invented new and useful Improvements in Electric Heating Devices for Running Water, of which the following is a specification.

Electric heating devices for running water are known, in which a controlling cock for the water and an electric switch are placed co-axially and connected together in such a manner that the current through the heating elements is supplied or cut off simultaneously with the opening or closing of the cock. The controlling cock, however, in the devices hitherto proposed, has been constructed in the form of a common plug cock, which has certain disadvantages in this connection. In the first place, in adjusting and grinding the cock plug, a substantially large variation in its longitudinal position must be provided for, which makes it difficult to effect a direct connection between the cock 20 and the switch. Furthermore the frictional resistance offered in the turning of the cock is always comparatively large, which is undesirable especially when it is connected to a switch with sudden interruption.

According to the present invention, the controlling device for the water, instead of a plug cock, consists of a rotatable slide valve, which possesses none of the disadvantages enumerated above.

An embodiment of the invention is illustrated in the accompanying drawing in which:

Figure 1 illustrates a side-elevation of the device. Fig. 2 a plan of same with parts of 40 the switch removed, and Fig. 3 a horizontal section through the valve.

A water or other liquid receptacle *a*, in which an electric heating apparatus *b* is immersed, is provided with a supply pipe *c* (for instance a hose) and a discharge valve *d*. The controlling member of the valve according to the invention consists of a rotatable plane slide *e* (Fig. 3) mounted on a vertical spindle *f* supporting also the rota-

table contact-piece *g* of a switch (Fig. 2). 50 On the upper part of the spindle is arranged a handle *h* (Fig. 1). The fixed contacts *k* of the switch preferably comprise the same angles around the shaft *f* as the openings in the slide face of the valve *d*, so that the current will flow through the heating elements 55 as long as the valve is open.

In order to lock the valve and the switch in different set positions there is placed on the spindle *f* a toothed disk *l*, with which a 60 spring operated latch or pawl *m* is adapted to engage. By this arrangement the device can be so controlled as to deliver in a given length of time a predetermined larger or smaller quantity of water at a lower or 65 higher temperature. The valve of course can, if desired, be arranged in the inlet as well as in the outlet conduit of the device.

The heating device, for facilitating its connection to a water supply pipe or the like 70 and to the vessel for receiving the water, can be made adjustable in the vertical direction with respect to its supporting frame *n* by means of a pinion *p* engaging a toothed rack *o* and rotatable by means of a crank 75 handle *r*. The pinion may be locked in various positions by means of a latch *t* engaging a toothed wheel *s*. The apparatus also may be permanently fitted in a water conduit. 80

Having now particularly described the nature of my invention and the manner of its operation, what I claim is:

In electric heating devices for running water with means for simultaneously controlling the heating current and the flow of water, the combination of a rotatable switch, a rotatable plane slide valve, a toothed disk, a shaft, said switch, plane and disk being mounted on said shaft and a spring-actuated 85 latch engaging said disk. 90

In testimony whereof I have signed my name to this specification in the presence of two subscribing witnesses.

HJALMAR LÖFQUIST.
